United States Patent Office

Des. 213,298
Patented Feb. 4, 1969

213,298

BILLIARD TABLE OR SIMILAR ARTICLE

Charles A. Porter, 10632 Paloma St.,
Garden Grove, Calif. 92640

Filed Mar. 11, 1968, Ser. No. 10,915

Term of patent 14 years

U.S. Cl. D34—3

Int. Cl. D21—04

Fig. 1.

FIGURE 1 is a top plan view of a billiard table or similar article showing my new design;

FIGURE 2 is a side elevational view; and

FIGURE 3 is an end elevational view;

The side opposite that shown in FIGURE 2 and the end opposite that shown in FIGURE 3 are substantially similar to those shown.

I claim:

The ornamental design for a billiard table or similar article, as shown and described.
